UNITED STATES PATENT OFFICE.

FRANK C. B. PAGE, OF NEW YORK, N. Y., ASSIGNOR TO E. W. BLISS COMPANY, A CORPORATION OF WEST VIRGINIA.

BLANK-HOLDING MEANS.

Application filed November 26, 1924. Serial No. 752,369.

To all whom it may concern:

Be it known that I, FRANK C. B. PAGE, a citizen of the United States, residing at New York, in the county of New York and State of New York, have invented certain new and useful Improvements in Blank-Holding Means, of which the following is a specification.

This invention relates to fluid pressure 10 cushions for use in drawing in one operation metal shapes or shells of a greater depth than is ordinarily possible to draw in one operation, and is particularly adapted though not necessarily limited in its use in 15 connection with what is termed a single action mechanical press.

In presses of this character there is provided a plurality of draw rings or blank holding means which co-operate with the die, the blank being held between the draw ring or blank holding means and the ram during the forming or shaping of the article. These draw rings are usually arranged one 20 within the other, one of the rings being held 25 by fluid pressure, against operation while the other ring is moved during the first portion of the cycle of operation of forming or shaping the blank over the stationary die and over the other die ring.

After the completion of the first portion 30 of the cycle of operation in forming or shaping the article, and during the same stroke of the ram, the article is further shaped, over the stationary die, the inner draw ring 35 being then moved against the fluid pressure acting thereupon.

The fluid pressure upon the inner draw ring must of necessity be of such a degree 40 that the ring will not be moved during the first portion of the formation of the article, with the result that during that portion of the cycle of operation of the press in which the inner draw ring is moved, the ram must 45 overcome the excess fluid pressure to complete the formation or shaping of the article. This results in a strain upon the crank shaft and clutches and reduces the capacity or scope of the press.

It is one of the objects of the present invention to overcome these difficulties and objections and to provide improved means to positively lock in a fixed position one of the blank holding members or draw rings while the other member or blank holding

means is allowed to remain movable under 55 the action of the ram, and to provide improved means for unlocking or releasing the locked member to allow it to move at a predetermined point or time in the cycle of operation of the press.

A further object is to provide improved means operating automatically to lock one 60 of the blank holding means against movement and to automatically unlock or release the blank holding means for movement.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating 70 this invention, and in which—

Figure 1 is a vertical, longitudinal sectional view of a blank holding means constructed in accordance with the principles of this invention, and showing the parts in their initial or starting position.

Figure 2 is a view similar to Figure 1 showing the parts in another position.

Figure 3 is a sectional view taken on line 3—3, Figure 2.

Figure 4 is a sectional view taken on line 4—4, Figure 5.

Figure 5 is a side elevation of the cushioning mechanism.

Figure 6 is a detail elevation of the cam member for controlling the movement of the actuating means for the locking mechanism.

Referring more particularly to the drawings the numeral 10 designates the bolster plate of a press, having mounted thereupon a stationary die member 11, with which a cutting member 12 co-operates.

Co-operating with the dies is another die member 13 carried by the ram or a movable part of the press, and this die member 13 100 co-operates with the member 12 to cut or shear the material 14 and is so shaped that it will pass between the dies 11 and 12 to shape the material over the die 11, all in the manner as well known in this art.

Encompassing the die 11 are a plurality of draw rings or blank holding members 15—16, one arranged within the other, and

these members 15 and 16 are respectively supported by means of pins 17 and 18 that pass through the bed plate or bolster 10.

Supported beneath the bolster plate 10 is a fluid actuated cushioning device preferably embodying an inverted cylinder 19 which telescopes over another cylinder 20, the latter resting upon a plate or member 21, which forms a closure for the cylinder and this plate or member is supported from the bolster or bed plate 10 in any desired or suitable manner such as by means of rods or bolts 22, which latter are threaded into the bolster plate 10 and also pass through the plate or member 21. Nuts or collars 23 are carried by these rods or bolts 22 for holding the parts in position.

The end 24 of the cylinder 20 serves as a piston operating in the cylinder 19, and suitable packing 25 may be provided between the piston and the cylinder.

Operating in the cylinder 20 is a piston 26 provided with suitable packing rings 27. A piston rod 28 is connected with the piston 26 and passes through the end 24 of the cylinder 20, suitable packing 29 being provided for the piston rod. This piston rod also passes through the end 30 of the cylinder 19 and a suitable packing 31 is provided for the piston at the point where it passes through the end of the cylinder 19. The cylinder 20 is provided with an inlet 32 to which is connected a supply pipe 33 that receives a supply of fluid from any suitable source. The cylinder 19 is also provided with an opening 34, connected with which is a suitable pipe 35 adapted to be supplied with fluid from any suitable source, and both of these openings 32 and 34 serve as outlets for the respective cylinders so that the fluid will flow into and out of the cylinders through the same respective openings.

Connected with the end of the piston 28 is an extension 36 preferably of a tubular construction and carried by the extension 36 are inwardly projecting flanges or portions 37, which are spaced from each other and are provided with parallel ribs 38 on the inner faces thereof. The extension 36 is of such a length that it will not interfere with the reciprocating movement of the piston 26 and will move with the piston.

The pins 17 which support the blank holding member or draw ring 15 and which pass through the bolster plate 10, rest upon the end of the extension 36 so that when the draw ring or member 15 is depressed in a manner to be hereinafter set forth, the piston 26 will, through the medium of the extension 36 and pins 17, be depressed against the fluid pressure within the cylinder 20.

Swiveled or otherwise connected with the bolster 10 to depend therebelow is a member 39, having ribs or teeth 40. This member 39 passes between the flanges 37, and the

ribs 40 on the member 39 will pass between the ribs 38 on the member 37. The member 39 is preferably provided with a shank 41 which is swiveled in the bed or bolster plate 10. The member 39 also projects into the tubular extension 36 and is provided with a head 42 having a bifurcated portion 43 which extends through an opening 44 in the extension 36. An arm 45 is rotatably supported upon a bar or rod 46, the latter being threaded by one extremity into the plate or member 21 as at 47, and the other extremity loosely passes into a socket 48 so that the rod 46 may be adjusted longitudinally. The arm 45 may be held in position by means of collars 49 on opposite sides thereof, and which collars are secured to the rod 46.

Supported by the cylinder 30 is a member 50 which is preferably hollow and through which member the extension 36 passes, and on the end of which member 50 the pins 18, which support the draw ring or blank gripping member 16, rest. When the member 16 is depressed by the die 13, the member 50 will also be depressed through the medium of the pins 18, and as the member 50 is lowered the cylinder 19 will be lowered against the fluid pressure therein. When the ram ascends, moving with it the die 13, the fluid pressure in the cylinder 19 will cause the latter to rise and with it the member 50.

This member 50 is provided with a slot 51, having a cam shaped portion 52 which is in alinement with the opening 44 in the member 36, and through which slot 41 the arm 45 projects so that the extremity of the arm 45 will stand within the bifurcation 43 in the head 42 of the member 39.

If desired an anti-friction roller 53 may be provided on the arm 45 where it passes through the slot 51.

Shoes or members 54 may be provided for assisting in holding the cylinders 19 and 20 in position when the cushion is connected to a press and held in an inclined position. These members 54 may be of any desired configuration and are adapted to be held against rotation in any suitable manner such as by means of dowel pins 55.

The member 50 may if desired, be provided with face plates 56 secured in position by means of suitable screws or bolts 57. This plate 56 is provided with a slot 58 of a configuration similar to the slot 44 in the member 50, and serves as a guide and a means for swinging the arm 45.

It will be manifest that inasmuch as the arm 45 is held against bodily movement and as the extremity of the arm passes into the bifurcation 43 on the head 42 of the member 39, the latter being swiveled or rotatably mounted upon the bolster plate 10, and as the member 50 with the cam groove 51 therein, together with the plate 56 and the cam groove 58 therein are reciprocated with the

cylinder 19, the arm 45 will be swung about its pivot during the reciprocation of the cylinder 19, and as this arm moves about its pivot it will rotate the member 39. The cam slots 51 and 58 are so located that when the member 39 has passed entirely through the flange or member 37 when the cylinder 19 is at the limit of its upward movement, the member 39 will be rotated so that the ribs 40 thereon will move into positions directly beneath the respective ribs on the member or flange 37, causing the proximate ends of these ribs to abut and thereby lock the piston 26, piston rod 28, extension 30, pins 17 and draw ring or blank holding member 15 against movement and in a position that the edge of the draw ring or member 15 will be substantially flush with the upper surface of the die 11. This is the position the parts 20 will assume at the beginning of the operation of the forming of the article and in the position as shown in Figure 1.

When the ram descends carrying with it the die 13, the edge of the die 13 will cooperate with the edge of the member 12 and the material 14 will be cut to the proper size. A further lowering movement of the ram will cause the material 14 to be gripped between the die 13 and the draw ring or blank holding member 16. The draw ring or blank holding member 16 being locked positively against movement with respect to the die 11 by means of the members 39 and 37 as before described, a further movement of the ram in a downward direction will cause the material 14 to be shaped over the die 11 and the member 15. This will depress the draw ring or blank holding member 16 against the fluid pressure in the cylinder 19, through the medium of the pins 18 and member 50. At the same time and as the member 50 descends at a predetermined time in the cycle of operation of the press, the cam grooves 51 and 58 will operate upon the arm 45 to swing the latter about its pivot and this will rotate the member 39 to cause the ribs 40 thereon to move into a position in alignment with the grooves between the ribs in the member 37, and the ribs on the member 37 in alignment with the grooves between the ribs 40 on the member 39. This operation will unlock the member 36, piston rod 28 and piston 26, as well as the draw ring or blank holding member 15.

A further movement of the ram in the same direction will then cause the material to be shaped over the die 11, the draw ring or blank holding member 15 being then depressed by the action of the die 13, against the fluid pressure in the cylinder 20, through the medium of the pins 17, extension 36, piston rod 28 and piston 26.

The member 40 will then remain in the same position until the completion of the stroke of the ram, and also upon the return

stroke of the ram and die 13 until the member 37 has passed beyond the member 39. At this time in the cycle of operation the cam grooves 51 and 58 will again swing the arm 45 about its pivot to rotate the member 39 so as to position the ribs 40 thereon in alignment with the ribs on the member 37 and thereby lock the draw ring or blank holding member 15 against operation.

Obviously the timing of the rotation of the member 30 may be controlled by adjusting the plate 56 upon the member 50.

With this improved construction it will be manifest that it is possible to draw or shape metal shells of a greater depth in one operation than has heretofore been possible on a single action mechanical press.

It will also be manifest that with this improvement, the size of the press used may be reduced for the reason that the crank of the press is not subjected to the spring or fluid pressure which has heretofore been necessary to hold the draw ring or blank holding member 15 in position during a portion of the cycle of operation of the press, as the member 15 will be positively locked and when unlocked the fluid pressure which has to be overcome by the action of the ram is only sufficient to render the draw ring or blank holding means active to grip the material with sufficient force to prevent wrinkling and at the same time permit the material to flow during the forming operation.

Furthermore by the use of the present invention, the necessity for providing balancing means for the necessary pressures required during one stage of the operation of the press, will be obviated.

While the preferred form of the invention has been herein shown and described, it is to be understood that various changes may be made in the details of construction and in the combination and arrangement of the several parts, within the scope of the claims, without departing from the spirit of this invention.

What is claimed as new is:

1. A draw press including a plunger, a plurality of blank holding means adapted to successively cooperate with the plunger to clamp the work, means for positively locking one of the said blank holding means against operation during the operation of the other blank holding means, the second recited means including cooperating elements relatively reciprocable and also rotatable one with relation to the other to lock and unlock the respective blank holding means, an actuator separate from the said locking means, and means operating automatically to operate said actuator to impart such relative rotary movement to the said elements at predetermined times in the cycle of operation of the press.

2. A draw press including a plunger, a

- plurality of blank holding means adapted to successively cooperate with the plunger to clamp the work, means for positively locking one of the said blank holding means 5 against operation during the operation of the other blank holding means, the second recited means including co-operating elements adapted for relative reciprocation and relative rotation to lock and unlock the respective blank holding means, an actuator separate from the blank holding means and the said locking means, and means responsive in its operation to the operation of one of the said blank holding means to render 10 said actuator active for imparting such relative movement to the said elements.
3. A draw press including a plunger, a plurality of blank holding means adapted to successively co-operate with the plunger 20 to clamp the work, means for positively locking one of the said blank holding means against operation during the operation of the other blank holding means, the second recited means including co-operating elements relatively rotatable one with relation 25 to the other to lock and unlock the respective blank holding means, means separate from the locking means and the blank holding means and operating automatically to 30 impart such relative movement to the said element, and means embodying cam devices adapted to be set whereby the time of operation of the last recited means in the cycle of operation of the press may be varied.
4. A draw press including a plunger, a plurality of blank holding means adapted to successively co-operate with the plunger to clamp the work, means for positively locking one of the blank holding means 40 against operation during the operation of the other blank holding means, the second recited means including two co-operating elements relatively rotatable one with relation to the other, and means operatively connected with one of said blank holding means 45 for automatically rotating one of said elements with respect to the other element to lock the elements against relative movement 50 and to release the elements for relative movement.
5. A draw press including a plunger, a plurality of blank holding means adapted to successively co-operate with the plunger to clamp the work, means for positively locking one of the blank holding means 55 against operation during the operation of the other blank holding means, the second recited means including two co-operating elements relatively movable with respect to 60 each other in different planes, an actuating device and means embodying adjustable cam like devices between which the said actuating device operates for automatically controlling the relative movement of said elements in one of said planes to lock said 65 elements against relative movement in the other of said planes and to unlock said elements for relative movement in the last recited plane.
6. A draw press including a plunger, a plurality of blank holding means adapted to successively co-operate with the plunger to clamp the work, means for positively locking one of the blank holding means against operation during the operation of the other blank holding means, the second recited means including two co-operating elements relatively movable with respect to each other in different planes, means embodying an actuating device for automatically controlling the relative movement of said elements in one of said planes to lock said elements against relative movement in the other of said planes and to unlock said elements for relative movement in the last recited plane, and means controlling the said actuating device and adapted to be set whereby the time of operation of the said controlling means in the cycle of operation of the press may be varied. 70
7. A draw press including a plunger, a plurality of blank holding means adapted to successively co-operate with the plunger to clamp the work, means for positively locking one of the said blank holding means against operation during the operation of the other blank holding means, the second recited means including two co-operating elements respectively provided with grooves and projections, the projections on one of said elements being movable through the groove in the other element, and means for imparting a relative rotary movement to the said elements to move the said projections and grooves out of alignment to cause the ends of the elements to abut to prevent a relative movement of the said elements and to move the projections and grooves into register to permit such relative movement of the elements. 80
8. A draw press including a plunger, a plurality of blank holding means adapted to successively co-operate with the plunger to clamp the work, means for positively locking one of the said blank holding means against operation during the operation of the other blank holding means, the second recited means including two co-operating elements respectively provided with grooves and projections, the projections on one of said elements being movable through the grooves in the other element, and means responsive in its operation to the operation of one of the said blank holding means for imparting a relative rotary movement to the said elements to move the said projections and grooves out of alignment to cause the ends of said elements to abut to prevent a relative movement of the said elements and to move the projections and grooves into 90
- 100
- 105
- 110
- 115
- 120
- 125
- 130

- register to permit such relative movement of the elements.
9. A draw press including a plunger, a plurality of blank holding means adapted to successively co-operate with the plunger to clamp the work, means for positively locking one of the said blank holding means against operation during the operation of the other blank holding means, the second recited 10 means including two co-operating elements respectively provided with grooves and projections, the projections on one of said elements being movable through the grooves in the other element, and means operating automatically at a predetermined time in the 15 cycle of operation of the press for imparting a relative rotary movement to the said elements to move the said projections and grooves out of alinement to cause the ends 20 of the said elements to abut to prevent a relative movement of the said elements and to move the projections and grooves into register to permit such relative movement of the elements.
- 25 10. A draw press including a plunger, a plurality of blank holding means adapted to successively co-operate with the plunger to clamp the work, means operable to positively lock one of the blank holding means against 30 operation during the operation of the other blank holding means, the said locking means including telescoping members provided respectively with co-operating ribs and 35 grooves, said members being movable out of telescoping relation, an actuating device for relatively rotating said members one with respect to the other to displace the co-operating ribs and grooves to lock the members against reciprocating movement, 40 and means for actuating said actuator.
11. A draw press including a plunger, a plurality of blank holding means adapted to successively co-operate with the plunger to clamp the work, means operable to positively lock one of the blank holding means against 45 operation during the operation of the other blank holding means, the said locking means including telescoping members provided respectively with co-operating ribs and 50 grooves, said members being movable out of telescoping relation, an actuating device for relatively rotating said members one with respect to the other to displace the co-operating ribs and grooves to lock the members against reciprocating movement, and means for actuating said actuator.
- members against reciprocating movement, and a cam device operatively connected with one of said blank holding means for actuating said actuator.
12. A draw press including a plunger, a plurality of blank holding means adapted to successively co-operate with the plunger to clamp the work, means operable to positively lock one of the blank holding means against operation during the operation of the other blank holding means, the said locking means including two members, a projection on one of the members and a groove in the other member to receive the projection to permit longitudinal reciprocation of said members one with respect to the other, one of said members being rotatable, a pivotally mounted arm operatively connected with the rotatable member for rotating it, and means responsive in its operation to the operation of one of the blank holders for swinging said arm to displace the said rib with respect to said groove to lock said members against relative reciprocation.
13. A draw press including a plunger, a plurality of blank holding means adapted to successively co-operate with the plunger to clamp the work, means operable to positively lock one of the blank holding means against operating during the operation of the other blank holding means, the said locking means including two members, a projection on one of the members and a groove in the other member to receive the projection to permit longitudinal reciprocation of said members one with respect to the other, one of said members being rotatable, a pivotally mounted arm operatively connected with the rotatable member for rotating it, and means responsive in its operation to the operation of one of the blank holders for swinging said arm to displace the said rib with respect to said groove to lock said members against relative reciprocation, the last recited means including a cam device adapted to be set, whereby the time in the cycle of operation of the press at which the said arm is actuated, may be raised.

In testimony whereof I have signed my name to this specification, on this 21st day of November, A. D. 1924.

FRANK C. B. PAGE.
